ABSTRACT: A cascade refrigeration system for installation where the machinery of the system is remote from the cooled space, in which an insulated bypass conduit withdraws at least some of the refrigerant available at the cooled space under a low-load condition, and delivers this refrigerant to a condenser in one of the stages, thus maintaining the circulation of refrigerant.

CASCADE REFRIGERATION SYSTEM WITH
REFRIGERANT BYPASS

BACKGROUND OF THE INVENTION

The so-called "cascade" refrigeration system is frequently used where relatively low temperatures in the controlled environment are desired. This arrangement usually involves an installation of evaporator coils in the controlled chamber, supplied with refrigerant by a conventional compressor-condenser system. The compressor receives the refrigerant in gaseous form from the evaporator, compresses it, and the heat of compression is removed by the condenser before returning the refrigerant in liquid form again to the expansion valve ahead of the evaporator. In the cascade arrangement, a second stage is used to cool the first stage condenser. The output of the compressor-condenser system of the second stage is passed through an expansion valve, and is delivered to the condenser in heat-exchanging relationship with the output of the first stage compressor. Such an arrangement is well-established refrigeration technique, and a number of stages in cascade relationship may be incorporated, if necessary.

There are a number of situations in which it becomes desirable to have a considerable distance between the compressor-condenser system and the controlled chamber. Where a central installation of refrigeration machinery is to supply a number of controlled chamber units, this remote relationship becomes a practical necessity. A problem arises, however, in that the delivery of the refrigerant from the first stage condenser to the evaporator in the controlled chamber over long distances has a tendency to cause the refrigerant to pick up sufficient heat to produce sections of refrigerant in gaseous form within the conduit. This is particularly true when the velocity of flow within the conduit is interrupted because of the interruption in the requirements of the evaporator. When the controlled chamber is down to the required temperature for the moment, the flow of refrigerant is either interrupted entirely, or sufficiently reduced in velocity to increase the problem of heat pickup. Where gaseous inclusions in the liquid line are present, the next cooling cycle will require that the entrapped gas in the liquid line will have to be pulled through the expansion device associated with the evaporator before refrigeration can begin. This lag in obtaining refrigeration causes cycling of the controlled temperature, and an improper balance in the primary refrigerant pressures.

SUMMARY OF THE INVENTION

This invention eliminates the possibilities of stagnation in the first stage liquid line by providing a bypass for the refrigerant at a point adjacent the first stage evaporator. During periods in which the refrigeration requirements of the evaporator are either reduced or nonexistent, a control valve responsive in some way to these temperature conditions diverts the refrigerant through an expansion device into an insulated conduit leading back to some convenient point on the first or second stage compressor-condenser system where this cooled refrigerant may be utilized to withdraw waste heat. Preferably, this point is between the second stage compressor and the conventional condenser associated with the output of that compressor.

The result of this arrangement is to maintain a constant flow of liquid refrigerant in the supply line to the remote evaporator, which eliminates the danger of heat pickup. By the addition of this insulated line as a third pipe in conjunction with the conventional two-pipe system, runs of a hundred feet or more are perfectly feasible. Test data and computations provide assurance that runs conceivably as long as 300 feet are entirely practical.

DESCRIPTION OF THE DRAWING

The drawing presents a schematic diagram of a typical two-stage cascade refrigeration system incorporating the present invention.

DESCRIPTION OF THE PREFERRED EMBODIMENT

The equipment located within the dotted rectangle 10 on the schematic diagram is associated with a remote chamber in which the temperature is controlled by the evaporator coils 11. These coils receive refrigerant from the distributor 12, after it has passed through the expansion device 13. Flow of refrigerant within the coils 11 is controlled by the temperature needs within the associated chamber by a detector line such as 5 the conduit 14, to which the expansion valve 13 is responsive. Refrigerant flow through and around the expansion valve 13 is controlled by the combined action of the flow control 15 and the liquid solenoids 16 and 17. The evaporated refrigerant gas from the coils 11 is received by the return conduit 18, through 10 which the refrigerant is delivered back to the first stage compressor 19 through the suction filter 20 and the vibration eliminator 21. An injection expansion valve 22 may be incorporated in the circuit, if desired, being supplied with liquid refrigerant by the line 23 communicating with the liquid line 24 15 delivering liquid refrigerant to the remote unit 10. The service valve 25, the vapor tank 26, the relief valve 27, and the purging valve 28 are standard installations in this type of system. A regulator valve 29 and a dump valve 30 are also 20 preferably incorporated, with the dump valve being actuated by pressure conditions communicated through the line 31.

The output of the first stage compressor is delivered through the discharge service valve 32 and the discharge vibration eliminator 33 and the pumpdown valve 34 to the oil separator 35. The refrigerant then passes through the line 36 25 to the condenser 37. Liquid refrigerant then proceeds through the filter dryer 38 and the liquid line 39 back to the remote unit 10. Oil extracted by the separator 35 is returned to the compressor through the line 40 and the oil filter 41.

The second stage compressor 42 delivers compressed refrigerant through the discharge service valve 43 and the vibration eliminator 44 to the water-cooled condenser 45. The control valves 46 and 47 are preferably incorporated in the system. A water-regulating valve 48 is provided in the water-supply line 49, and a relief valve 50 should also be present. Condensed refrigerant from this section of the second stage is carried by the conduit 51 through the filter dryer 52, the liquid indicator 53, and the liquid solenoid 54 to the expansion valve 55. This valve is controlled by the detector line 56, and delivers expanded refrigerant to the distributor 57. This expanded refrigerant is applied in heat-exchanging relationship to the compressed refrigerant of the first stage by the condenser 37. Spent refrigerant from the condenser 37 is returned through the line 58, the suction filter 59, the vibration eliminator 60, and the service valve 61 to the second stage compressor. An additional element in the two-stage system may be the water-cooled desuperheater 62 installed in heat-exchanging relationship with the output of the first stage compressor. The water lines 63 and 64 provide the cooling circuit controlled by 50 the valve regulator 65 responsive to temperature conditions in the line 36. The water line 49 may be considered as the pressure source, with the line 66 functioning as the return.

The description to this point has summarized a relatively standard cascade refrigeration system within which the present invention may be incorporated. The arrangement for maintaining a constant flow of liquid refrigerant in the line 24 centers in the provision of the bypass circuit which includes an insulated conduit 67 receiving the output from the expansion valve 68 controlled as a function of conditions in the evaporator coils 11 communicated by the line 69. Liquid refrigerant is supplied to the expansion valve 68 by the bypass supply line 70 communicating with the liquid line 24 at a point adjacent or within the remote unit 10. The liquid diverted through the expansion valve 68 passes through the liquid solenoid 71. The 65 expanded refrigerant from the valve 68 is conducted back to the bypass heat exchanger 72 through the insulated line 67, and this refrigerant is returned from the bypass heat exchanger to the input of the first stage compressor by the return line 73. Waste heat from the output of the second stage compressor is therefore removed from the refrigerant that 70 75

stage by the condenser 72, which would otherwise have to be removed by the water-cooled condenser 45. The supply of water can therefore be reduced as a result of the utilization of this source of cooling. The various valves and other control devices may be set in such a manner as to maintain a continuous flow of refrigerant in the liquid line 24, which is either supplied to the coils 11, or diverted through the bypass line 67. The use of a bypass, per se, in a refrigeration system of a different type, and for different purposes, has been noted in the R. E. Gould et al. U.S. Pat. No. 2,332,711.

I claim:

1. A cascade refrigeration system including a first stage having a compressor, a remote heat-absorbing evaporator unit, and a condenser, and also including a second stage having a compressor and a condenser, and including conduit means connecting the output thereof with said first stage condenser, said first stage having a liquid conduit extending from said condenser unit to said first stage evaporator unit, and a return gas conduit extending from said first stage evaporator unit to the input of said first stage compressor, wherein the improvement comprises:

10

a bypass circuit communicating with said liquid conduit at a point adjacent said first stage evaporator unit, and including a control valve adjacent said point and responsive to temperature conditions associated with said first stage evaporator unit and adapted to divert refrigerant into said bypass circuit, said circuit also including expansion means, a bypass heat exchanger in heat-exchanging relationship with the output of one of said compressors, a heat-insulated conduit extending from said expansion means to said bypass heat-exchanger, and a return conduit extending from said bypass heat exchanger to a point communicating with the input into one of said compressors.

15 2. A system as defined in claim 1, wherein said bypass return conduit communicates with the input of said first stage compressor.

3. A system as defined in claim 1, wherein said bypass heat exchanger is disposed with the output thereof connected to the input of said first stage condenser.
